UNITED STATES PATENT OFFICE

ARTHUR L. WOODBRIDGE, OF CHICAGO, ILLINOIS

STAIRWAY-PLATFORM CONSTRUCTION

Application filed March 17, 1928. Serial No. 262,378.

This invention relates to a stairway construction and has special reference to metal stairways of a standardized construction which are adaptable to any building.

More particularly, this invention relates to the construction of the intermediate platform or landing between two flights or runs of stairs and the structure directly associated therewith, the principal object thereof being to provide a maximum strength in the aforementioned construction generally and to minimize the cost of the material and the amount of labor required to fabricate and to install the same.

In the present construction, the floor plates of the platform are of a unitary construction and the reinforcing portions therefor form an integral part of the plates, extending above the bottom surface thereof. Aside from the saving of labor and materials and the strengthening of the construction, this arrangement provides a finished and pleasing appearance when viewed from the underneath side of the platform and eliminates the unsightly appearance of reinforcing T's angle iron connecting members, and the like of the usual constructions.

Other objects and advantages will hereinafter be referred to and for a better understanding of the nature, characteristics and scope of this invention, reference may be had to the accompanying drawings and the following description, in which drawings:

Figure 1 is a top plan view of the construction embodied in this invention before the composition or cement filling is disposed therein;

Fig. 2 is a vertical sectional view taken on the line 2-2 of Fig. 1 after the composition or cement filling is disposed therein;

Fig. 3 is an enlarged detail sectional view of a portion of Fig. 2 taken on the line 3-3 of Fig. 1;

Fig. 4 is a vertical sectional view taken on the line 4-4 of Fig. 1 of an intermediate portion of the platform.

Fig. 5 is a vertical sectional view taken on the line 5-5 of Fig. 1; and,

Fig. 6 is a perspective view of the construction shown in Fig. 1.

Referring now to the drawings, an intermediate platform or landing is shown comprising preferably a rectangular framework formed of stringers 10, 11, and 12 suitably supported in wall bearings as at 13 and 14. However, where bearings in walls are not possible, these stringers may be supported from hangers extending from any of the usual beams employed in building constructions. In the present construction, the stringer 10 has one end extending beyond the confines of the rectangular platform and is embedded in the wall. The other end of the stringer 10 is suitably secured to the stringer 11 which latter extends beyond the confines of the platform and is supported in a wall bearing. The stringer 12 is secured to the face of the stringer 10 by means of an angle bracket or other suitable means, this stringer, together with stringer 11, being preferably arc welded to stair stringers 15 and 16, respectively. All of the stringers thus far described are preferably formed of heavy steel plates pressed into the shape of channels, although it is apparent that the ordinary structural steel channels may be employed. The platform is carried at the stair end thereof by a beam 17 in the form of a channel, the beam being in turn supported by and between the stringers 11 and 12, and an angle bracket 18 being bolted or riveted to each stringer and to the beam 17.

An angle iron member 19 extends across and is secured to the face of the stringer 10, the stringers 11 and 12 having similar angle iron members 20 and 21 secured thereto and extending thereacross. It will be particularly noted that these angle iron members are inverted with reference to the usual construction, the vertical flange being pointed upwardly instead of downwardly. A plurality of floor plates 22 are disposed between the stringers and rest upon the horizontally extending portions of the angle iron members 19, 20 and 21. These floor plates comprise metal sheets having their inner edges 23 bent upwardly at substantially right angles to the planes of their surfaces. The

edges 23 of adjacent floor plates are suitably secured together as by means of nuts and bolts 24 thereby providing integrally formed reinforcing portions and supports therefor and doing away with angle iron bars, stringers or supports, T-castings to support the ends of such angle bars, and the like, all of which is costly and unsightly.

The ends of the floor plates at the stair 10 end of the platform are bent upwardly and then outwardly to form a continuous flange 24 for resting on the upper portion of the beam 17. This flange 24 eliminates the employment of angle irons such as are required 15 on the stringers 10, 11 and 12, or otherwise, and holds the floor plates in a positive relation with the platform.

The inside stair stringer 25, shown more particularly in Figs. 5 and 6 of the drawings, 20 is suitably fastened to a newell post 26, which latter is, in turn, suitably secured to the beam 17. Angle iron struts 27 are secured to the stringers 15 and 25 and carry a one-piece step and riser 28, the step being secured to 25 the riser next below by means of bolts or rivets. A plate 29 is secured between the flange 24 and the beam 17 and extends outwardly to be connected to the riser portion of the member 28, the upper end of the riser 30 being formed into a nose and extending upwardly from the connection. Concrete or any suitable composition may be disposed in the recessed portions provided by the floor plates 22 to the height of the nose portion 35 of the riser 28. Each of the steps is similarly filled with a concrete or a composition to the height of the nose portion, which latter is formed on each of the stairs in a manner similar to that as described with reference 40 to the platform.

As a result of this construction, a substantially flat surface is obtained on the underneath side of the platform and there are no depending portions extending from that surface. This structure affords a finished and pleasing appearance. The floor plates of the platform are effectively reinforced by means of the upwardly extending connecting edges 23 whereby a unitary construction is obtained and the various tees and angle iron struts or supports of prior construction are eliminated. Also, the tread filling when in place reinforces, strengthens, and supports the connection formed by the upturned flanges or edges of the plates which are thus embedded in the filling material. This effect is enhanced when the filling material is adhesive in character.

While but a single embodiment of this invention is herein shown and described, it is to be understood that various modifications thereof may be apparent to those skilled in the art without departing from the spirit and scope of this invention and therefore the

same is to be limited only by the scope of the prior art and the appended claims.

I claim:

1. A platform for metal stairways comprising a metal framework, a flooring for supporting a filling of concrete or the like comprising a plurality of plates having upwardly extending flanges secured together and embedded in said concrete, and supporting members secured to said framework for supporting said plates, said members extending upwardly from the plane of said plates. 70

2. A platform for metal stairways comprising a metal framework, a flooring for supporting a filling of concrete or the like comprising a plurality of plates having upwardly extending flanges secured together and embedded in said concrete, and angle iron supports secured to said framework, said plates resting on the horizontal portion of said angle iron supports, the vertical portion of said supports extending in a plane above said plates. 80

3. A platform for metal stairways comprising a metal framework, a flooring for supporting a filling of concrete or the like comprising a plurality of interconnected plates embedded in said concrete, one end of said flooring having a flanged portion integrally formed therewith directly secured to one member of said framework, and supporting members secured to the remaining members of said framework for supporting said flooring. 90

4. A platform for metal stairways comprising a rectangular metal framework, supporting members disposed on three members of said metal framework, a flooring comprising sheet metal members resting on said supporting members, said flooring having a flange formed integrally therewith directly secured to the remaining member of said framework. 100

5. A platform for metal stairways comprising a framework of metal stringers, a flooring for supporting a filling of concrete or the like comprising a plurality of plates having upwardly formed projections thereon for interconnecting said plates, one edge of said plates being bent upwardly and outwardly to form a continuous flange, said flange resting on and being secured to one stringer of said framework, and supporting members secured to the remaining stringers of said framework for supporting said flooring, said supporting members extending upwardly from the plane of said plates. 110

6. In an intermediate platform construction for metal stairways, the combination with a rectangular metal frame, of a recessed flooring in said frame, said flooring comprising a plurality of metal plates having flanges at their adjacent edges extending perpendicularly to the plane of the plates, said flanges being secured together, and angle bar sup- 120

ports for the edges of said plates along the frame, said angle bars having their vertical flanges extending upwardly and secured to the inside of the frame members, said plates resting on the upper side of the horizontal flanges of said angle bars.

7. In an intermediate platform construction for metal stairways, the combination with a rectangular metal frame, of a recessed flooring in said frame comprising a plurality of metal plates extending thereacross, said plates having their edges adjacent to one side of the frame bent upwardly and outwardly over one side member of the frame, said plates also having their adjacent edges bent upwardly to form flanges, said flanges secured together, the other edges of the plates being supported by angle bars secured to the other frame member with their vertical flanges extending upwardly and the plates resting on top of their horizontal flanges.

8. A reenforced concrete stair platform comprising: two wall-supported end beams; a wall-supported side beam; a front side beam, extending between said end beams and spaced outwardly from said wall side beam; shouldered-supporting elements on a plurality of said beams; a plurality of separate formed sheets seated upon said shouldered elements, said sheets being abutted and covering the entire area of the platform defined by said beams and providing therewith a form for the concrete, said sheets having upwardly turned integral flanges extending cross wise between said wall and front side beams; and a layer of concrete on said sheets and in which said flanges are imbedded.

9. A reenforced concrete stair platform comprising: wall-supported end beams and a wall-supported side beam; a front side beam, supported at its ends by said end beams and spaced from said wall side beam; ledge supporting means carried by a plurality of said beams on their inner faces; a plurality of metal sheets supported on said means and secured thereto and arranged in a series from one end beam to the other end beam, said sheets having flanges along their adjacent edges extending between said side beams; and a layer of concrete on said sheets.

10. In a stair platform, the combination with two end and one side wall-supported channels, corresponding to three sides of the platform; of a fourth channel supported at its ends by said end channels and spaced outwardly from said first-named side channel; angle irons extending along and secured to the inner faces of a plurality of said channels below the top edges thereof and in a common plane; a series of independent metal sheets supported upon said angle irons and secured thereto around their edges, said sheets covering the entire area defined by the channels, said sheets, along adjacent edges,

having upwardly extending, integrally formed flanges, said flanges extending between said wall and fourth channels and constituting cross-beams; and a layer of concrete on said sheets and in which said flanges are imbedded.

11. A reenforced concrete platform structure including: three wall-supported beams, one along one side and two at the ends of the platform; a fourth beam supported at its ends by said end beams and spaced from said side beam; ledge supporting elements extending continuously along the inner faces of a plurality of said beams and disposed on a common level and below the tops of the beams; a plurality of separable metal sheets supported at their edges upon said elements and secured thereto, said sheets and beams constituting a form for the concrete, said sheets having integrally formed upstanding flanged edges extending in a direction between said side beams; and a layer of concrete overlying all of said sheets and of a depth greater than said flanges, the bottom sides of said sheets presenting an unbroken flat surface on the underside of the platform.

In witness whereof, I have hereunto subscribed my name.

A. L. WOODBRIDGE.
